US00D786419S

(12) **United States Design Patent** (10) Patent No.: **US D786,419 S**
 Rindoks (45) Date of Patent: ** May 9, 2017

(54) **BAFFLE FOR FUME HOODS**

(71) Applicant: **Kewaunee Scientific Corporation**, Statesville, NC (US)
 (72) Inventor: **Kurt P. Rindoks**, Statesville, NC (US)
 (73) Assignee: **Kewaunee Scientific Corporation**, Statesville, NC (US)

(**) Term: **15 Years**(21) Appl. No.: **29/564,757**(22) Filed: **May 16, 2016**(51) LOC (10) Cl. **23-04**

(52) U.S. Cl.

USPC ..... **D23/386**(58) **Field of Classification Search**

USPC ..... D23/323, 328, 333, 335, 336, 337, 341, D23/352, 357, 370, 385, 386, 397, 399, D23/400, 406, 411, 413, 499; D13/182 CPC B64C 11/04; B64C 11/16; B64C 11/18; B64C 11/20; B64C 2001/009; F03D 3/062; F03D 11/04; F04D 19/002; F04D 25/068; F04D 25/088; F04D 19/00; F24F 1/0018; B64D 13/02; E04C 2/427; E06B 3/5892; B24B 37/04; B01D 46/00

CLAIM

The ornamental design for a baffle for fume hoods, as shown.

DESCRIPTION

FIG. 1 is a front perspective view of a baffle for fume hoods, showing a first embodiment of my new design; FIG. 2 is a front elevational view thereof; FIG. 3 is a rear elevational view thereof; FIG. 4 is a right side elevational view thereof; FIG. 5 is a left side elevational view thereof; FIG. 6 is a top plan view thereof; FIG. 7 is a bottom plan view thereof; FIG. 8 is a front perspective view of a baffle for fume hoods, showing a second embodiment of my new design; FIG. 9 is a front elevational view thereof; FIG. 10 is a rear elevational view thereof; FIG. 11 is a right side elevational view thereof; FIG. 12 is a left side elevational view thereof; FIG. 13 is a top plan view thereof; FIG. 14 is a bottom plan view thereof;

FIG. 15 is a front perspective view of a baffle for fume hoods, showing a third embodiment of my new design;
FIG. 16 is a front elevational view thereof;
FIG. 17 is a rear elevational view thereof;
FIG. 18 is a right side elevational view thereof;

FIG. 19 is a left side elevational view thereof;
FIG. 20 is a top plan view thereof; and,
FIG. 21 is a bottom plan view thereof.
